UNITED STATES PATENT OFFICE.

AARON J. JACOBS AND HARRY M. JACOBS, OF BROOKLYN, NEW YORK.

DESIGN FOR A SCALE FRAME.

Application filed May 22, 1926. Serial No. 17,817. Term of patent 14 years.

To all whom it may concern:

Be it known that we, **AARON J. JACOBS** and **HARRY M. JACOBS**, citizens of the United States, residing at Brooklyn, in the county of Kings and State of New York, have invented a new, original, and ornamental Design for Scale Frame, of which the following is a specification, reference being had to the accompanying drawing, forming part thereof.

The figure is a perspective view of a scale frame showing our new design.

We claim:

The ornamental design for a scale frame as shown.

AARON J. JACOBS.
HARRY M. JACOBS.
